UNITED STATES PATENT OFFICE

GUSTAV B. JENSEN, OF NEW YORK, N. Y., ASSIGNOR TO VADSCO SALES CORPORATION, OF NEW YORK, N. Y., A CORPORATION OF NEW YORK

DESIGN FOR A TOILET ACCESSORY CONTAINER

Application filed August 14, 1930. Serial No. 36,668. Term of patent 7 years.

To all whom it may concern:

Be it known that I, GUSTAV B. JENSEN, a citizen of Denmark, residing at New York city, county of New York, borough of Manhattan, and State of New York, have invented a new, original, and ornamental Design for Toilet Accessory Containers, of which the following is a specification, reference being had to the accompanying drawings, forming a part thereof.

I claim:

The ornamental design for a toilet accessory container as shown.

GUSTAV B. JENSEN.
